UNITED STATES PATENT OFFICE.

GUIDO FORNACA, OF TURIN, ITALY, ASSIGNOR TO F. I. A. T., A CORPORATION OF NEW YORK.

COMBUSTION-ENGINE.

1,190,252.

Specification of Letters Patent. Patented July 4, 1916.

Application filed December 17, 1909. Serial No. 533,554.

To all whom it may concern:

Be it known that I, GUIDO FORNACA, a subject of the King of Italy, residing at Turin, in the Kingdom of Italy, have invented certain new and useful Improvements in Combustion-Engines, of which the following is a full, clear, and exact specification.

This invention relates to combustion engines and has particular reference to a casting for multiple cylinder engines wherein the cylinder, valve chambers, and the water jacket may all be cast integrally at one operation, and then subsequently finished and machined to complete the engine.

It is desirable to cast as many cylinders and associated parts in one, as possible, because thereby the various operations on different cylinders can be simultaneously performed with a consequent saving in cost, and also the alignment of the cylinders in the complete engine is more easily maintained. Furthermore, it is especially desired that the charge inlet pipe to the inlet chambers be water jacketed, in order that charge may be supplied at a substantially constant temperature. Also it may be desirable to have the exhaust chambers and exhaust conduit water jacketed in order that the exhaust gases may be more quickly cooled and thereby a more noiseless operation of the engine obtained. In attaining these objects I propose to form in a single casting, a plurality of cylinders and water jackets therefor, valve chambers together with inlet and outlet pipes included within the water jacket, all constructed and arranged in such manner that the casting can be easily cored and finished, while at the same time insuring the proper proportioning of all the parts and enabling them to be easily cast.

The invention will be more fully understood in connection with the description of the accompanying drawings wherein,

Figure 1 is a plan view, partly in section of an engine embodying the invention. Fig. 2 is a side elevation, partly in section. Fig. 3 is a vertical section through the inlet valve chamber. Fig. 4 is a similar section through the exhaust valve chamber, and

Fig. 5 is a plan view partly in section of a modified form of the invention.

The invention as shown herein is embodied in a four cylinder engine wherein 55 1, 1, 1, 1, represent the bases of the cylinders, to the lower portions of which will be secured the usual crank case, shaft bearings and other parts not necessary to be shown herein. Combustion engine cylinders 60 are usually water jacketed at the head and on the sides to about the length of the stroke of the piston, which is the case herein.

2, 2, 2, 2, represent the cylinders proper and are adapted to receive the usual working pistons, not shown herein. Surrounding the cylinders 2, is a water jacket casing 3, forming a water jacket 4, this casing 3 being made large enough to surround the exterior of the cylinders 2, the inlet chambers 5, and exhaust chambers 6. Each of these inlet and exhaust chambers opens into the compression space 7, of one cylinder through valve seats 8, and the valves 9, will be mounted to seat on said valve seats 8, in 75 the usual manner. Each of the compression spaces 7, is separated from that of the adjoining cylinder of each pair by a wall 10, located above the wall containing the valve seats 8, it being seen that below the 80 valve seats 8, there must be a wall 11, between the inlet chambers 5, and the exhaust chambers 6, of each cylinder. 12 are valve stem guides for each valve, both inlet and exhaust. By this arrangement of inlet and 85 exhaust gas passages or manifolds closely adjacent the valve chambers, with the valve stem guides between, the width of the motor is diminished and compactness secured. Consequently, lightness in weight in proportion to the power results, and also even 90 temperature throughout the casting.

15 represents the manifold inlet pipe entering on one side of the water jacket casing 3, and passing between the two middle cylinders, which are spaced apart for this purpose, and then dividing into two pipes 16, which lead respectively to the opposite pairs of inlet chambers 5 below the valves. Inasmuch as it is desirable that each inlet valve 100 should be approximately the same distance from the carburetor, the inlet chambers of

each pair of cylinders are made adjacent each other and thereby, the end cylinders will take the same amount of charge as the middle cylinders.

5 It will be seen that each inlet pipe 16, opens through a wide port 18, into the double inlet chamber 5, below the inlet valve seats 8, and that the inlet pipes 15, 16, and the inlet chambers 5, are all contained within

10 in the outer casing 3, and consequently within the water jacket 4.

The exhaust pipe 20, extends below the inlet chambers 5, and the exhaust chambers 6, but communicates only with the exhaust 15 chambers 6 through ports 21, see Fig. 4, it being observed that the exhaust pipe 20, is also within the water jacket 4, though this exhaust pipe may be placed outside the water jacket without departing from the 20 scope of the invention. It will be understood that the valves will be operated in any suitable manner and properly timed to control the admission and the exhaust of the gases.

25 As thus far described, the outer casing 3, is integral with the cylinder heads 22, and in order to provide a water jacket for the cylinder heads, the casting is provided with a beading 24, around the top and outside 30 the diameter of the cylinders 2, and also there are provided integral strengthening ribs 25, 26, on the cylinder heads. The beading 24, being machined smooth is covered with a cap 27, covering all of the cylinder 35 heads and resting on lugs 28, about at the center of each cylinder. These lugs 28 may be bored for pet-cocks 29. The spark plugs 30, are inserted in screw plugs 31, screwed into the tops of the casting just outside the 40 cover and preferably over the inlet valves, so as to render the valves accessible. A similar screw plug 32 will be placed over the exhaust valves, so that by removing these screw plugs 31 or 32 the valves can be 45 inserted or removed and the valve seats ground.

The water jacket cover 27, is also provided with water or outlets 34, connected with a pipe not shown, leading to the water 50 cooler, and the water may be admitted to the water jacket at any suitable point, as, for instance, at inlet 36, or there may be a plurality of inlets.

In Fig. 5, is shown a modification, where- 55 in the inlets are all at one side of the casting and the exhausts are on the other side, similar parts being similarly numbered and readily understood without further description.

60 From the foregoing description the objects and advantages of the invention will be fully understood. By forming the water jacket cover separately, the coring between the cylinders and the other parts can be 65 more readily done, and also the castings can

be easily inspected for inequalities, and the cores easily removed. Where the water jacket cover is cast integrally with the cylinder head, defects are very likely to occur but cannot be detected. At the same time, 70 by this invention, the cylinder heads are strengthened by ribs, and the water jackets are readily accessible by removing the cover.

It will be seen that various modifications 75 and changes in the specific construction here described may be made without departing from the scope of the invention.

Having thus described my invention I declare that what I claim as new and desire 80 to secure by Letters Patent, is—

1. A multiple cylinder casting for an explosion engine comprising at least four cylinders having heads integral therewith, a manifold inlet pipe integral therewith and inclosed within the casting having branches of equal length connected to pairs of said cylinders, an exhaust pipe having a connection with each of said cylinders and extending lengthwise of the casting, and a water jacket integral with said casting and surrounding said cylinders and said manifold inlet pipe. 85

2. A casting for a multiple cylinder explosion engine comprising at least four cylinders, a manifold inlet pipe integral therewith and inclosed within the casting having branches of equal length connected to pairs of said cylinders, an exhaust pipe connected to each cylinder, and a water jacket casting 90 outside said cylinders and integral therewith. 95

3. A multiple cylinder casting for an explosion engine comprising at least four engine cylinders, a manifold inlet pipe integral therewith extending transversely between pairs of said cylinders and having branches of equal length leading through inlet valve chambers to the cylinders of each pair, an exhaust valve chamber for each cylinder adjacent its inlet valve chamber, an exhaust pipe having a connection with each of said exhaust valve chambers, and a water jacket integral with said casting and surrounding said cylinders and 105 said manifold inlet pipe. 110

4. A casting for a multiple cylinder explosion engine comprising a plurality of pairs of cylinders having integral heads, an inlet and an exhaust chamber for each cylinder, an exhaust pipe connected to the exhaust chambers, an inlet pipe passing between pairs of said cylinders and branching to said inlet chambers, and a water jacket inclosing said cylinders and said inlet pipe. 120 125

5. A casting for a multiple cylinder explosion engine comprising at least four cylinders, an inlet for each cylinder, a manifold inlet pipe integral with the cylinders 130

opening from one side of the casting and connected to the several inlets by passages of approximately equal length, and a cooling jacket outside said cylinders and mani-
5 fold.

6. A casting for a multiple cylinder engine comprising a plurality of pairs of cylinders, an inlet and an exhaust chamber for each cylinder, a transverse inlet pipe 10 passing between pairs of said cylinders and branching to said inlet chambers, said branches being of equal length, and means for cooling said casting.

7. A multiple cylinder casting for an explosion engine comprising a plurality of pairs of cylinders having integral heads, an inlet valve chamber disposed on one side between each of said pairs of cylinders and having integral cast walls provided with 15 openings into the cylinders of each pair, a passage connecting said valve chambers having walls integral with said casting, an external passage opening into said connecting passage at an intermediate point, an exhaust passage having a connection with each cylinder, and a water jacket surrounding said cylinders, and said inlet passages.

8. A casting for a multiple cylinder explosion engine comprising at least four cylinders, a common inlet for each pair of cylinders, a manifold inlet pipe integral with the cylinders opening from one side of the casting between intermediate cylinders and connected to the inlets of each pair by passages of approximately equal length, and a cooling jacket outside said cylinders and manifold.

9. A casting for a multiple cylinder engine comprising at least four closed end cylinders, certain of which having common dividing walls, inlet and exhaust chambers opening into the respective cylinders, a water jacket casing surrounding said cylinders and chambers, and inlet and exhaust 40 pipes connected to the respective chambers and included within said water jacket.

10. A multiple cylinder casting for an explosion engine comprising a plurality of pairs of cylinders having integral heads, 45 an inlet valve chamber disposed on one side between each of said pairs of cylinders and having integral cast walls provided with openings into the cylinders of each pair, a passage connecting said valve chambers having walls integral with said casting, an external passage opening into said connecting passage at an intermediate point, an exhaust passage having connections with each cylinder, and a water jacket surrounding said cylinders, and said inlet and exhaust passages.

11. A multiple cylinder casting for an explosion engine comprising a plurality of pairs of cylinders, an inlet valve chamber 50 for each of said pairs of cylinders and hav-

ing integral cast walls provided with openings into the cylinders of each pair, an exhaust valve chamber for each cylinder in alignment with said inlet valve chambers, a passage adjacent the cylinder walls connecting said inlet valve chambers, said exhaust passage having walls integral with said casting, an external passage opening into said connecting passage at an intermediate point, and an exhaust passage below said exhaust valve chambers, said exhaust passage being connected to said exhaust valve chambers.

12. A multiple cylinder casting for an explosion engine comprising a plurality of pairs of cylinders, an inlet valve chamber for each of said pairs of cylinders and having integral cast walls provided with openings into the cylinders of each pair, an exhaust valve chamber for each cylinder in alignment with said inlet valve chambers, a passage adjacent the cylinder walls connecting said inlet valve chambers, said exhaust passage having walls integral with said casting, an external passage opening into said connecting passage at an intermediate point, an exhaust passage below said exhaust valve chambers, said exhaust passage being connected to said exhaust valve chambers, and a water jacket surrounding said cylinders, and said inlet and exhaust passages.

13. In a multiple cylinder engine casting, the combination with a plurality of cylinders having integral heads and a water jacket surrounding the sides and heads, of a removable cover for said water jacket, an inlet and an exhaust chamber for each cylinder, inlet and exhaust pipes connected with said respective chambers, a water inlet 100 through the side water jacket, and a discharge outlet through said cover, said inlet pipes being manifolded within the outer surface of the casting, and having a common inlet at an intermediate portion of said casting.

14. A casting for a multiple cylinder engine comprising a plurality of cylinder groups, each group comprising a plurality of cylinders closed at one end, a transverse 115 manifold inlet pipe, a portion of said manifold being disposed between adjacent groups, and a water jacket surrounding said cylinders and said manifold.

15. A casting for a multiple cylinder engine comprising a plurality of groups of cylinders, the cylinders of each group being in contact with one another, and a manifold inlet pipe having branches leading to each of said cylinders, a portion of said 120 manifold pipe extending transversely of the casting between adjacent groups of cylinders.

16. A casting for a multiple cylinder engine comprising at least four cylinders, an 125

integral exhaust outlet chamber adjacent each cylinder, a longitudinally extending exhaust manifold integral with said cylinders and chambers and connected thereto, 5 and a water jacket outside said cylinders and exhaust manifold and integral therewith.

17. In a multiple cylinder casting, integral cylinders and heads, a water jacket in- 10 closing said cylinders, an inlet and an ex- haust valve chamber for each cylinder on one side of said casting within said water jacket, inlet and exhaust manifolds within said water jacket and adjacent said valve 15 chambers, and valve stem guides formed in said casting adjacent said inlet and exhaust manifolds.

18. In a multiple cylinder casting, integral cylinders and heads, a water jacket in- 20 closing said cylinders, an inlet and an ex- haust valve chamber for each cylinder on one side of said casting within said water jacket, inlet and exhaust manifolds within said water jacket and adjacent said valve 25 chambers, the exhaust passage being below the respective exhaust chambers, and valve stem guides formed in said casting adjacent said inlet and exhaust manifolds.

19. A casting for a multiple cylinder ex-

plosion engine comprising at least four cyl- 30 inders, an inlet for each cylinder, a mani- fold inlet pipe integral with the cylinders opening from one side of the casting and connected to the several inlets by passages of approximately equal length, a water 35 jacket outside said cylinders and manifold having a water inlet adjacent one end, and a removable cover having a water outlet.

20. A casting for a multiple cylinder ex- 40 plosion engine comprising a plurality of groups of cylinders, a common inlet for each group, a manifold inlet pipe integral with the cylinders opening from one side of the casting between adjacent groups of said cyl- 45 inders and connected by oppositely extend- ing branches to each inlet, an exhaust outlet for each cylinder integral therewith, a lon- gitudinally extending integral exhaust manifold connected to said outlets, and an integral water jacket outside said cylinders 50 and said manifolds.

In testimony whereof I affix my signature, in presence of two witnesses.
